UNITED STATES PATENT OFFICE

161,440

STRAP BUCKLE FOR CHILDREN'S GARMENTS

Jacob Gomberg, Chicago, Ill.

Application June 16, 1950, Serial No. 10,581

Term of patent 14 years

(Cl. D17—1)

To all whom it may concern:

Be it known that I, Jacob Gomberg, a citizen of the United States of America, residing in the city of Chicago, county of Cook, State of Illinois, have invented a new, original, and ornamental Design for a Strap Buckle for Children's Garments, of which the following is a specification, reference being had to the accompanying drawing, forming part thereof, and wherein:

Fig. 1 shows a plan view of the buckle, and
Fig. 2 shows a longitudinal edge view.

I claim:

The ornamental design for a strap buckle for children's garments, as shown.

JACOB GOMBERG.
